UNITED STATES PATENT OFFICE.

WILLIAM H. GRINDLEY, OF CONGLETON, ENGLAND.

DESIGN FOR A DISH.

SPECIFICATION forming part of Design No. 29,618, dated November 8, 1898.

Application filed September 9, 1898. Serial No. 690,602. Term of patent 3½ years.

To all whom it may concern:

Be it known that I, WILLIAM H. GRINDLEY, a subject of the Queen of Great Britain, residing at Congleton, Cheshire, England, have 5 invented a certain new and original Design for a Dish; and I do hereby declare the following to be a full, clear, and exact description of the same, reference being had to the accompanying drawing, forming part hereof.

10 In the drawing the figure is a plan view of a dish embodying my design, the leading features of which are as follows:

15 A center quatrefoil *a* in outline is placed near the edge of the dish. Springing from this on the right is a single curved line *b*, which at first is approximately parallel to the outer edge of the dish, but which runs away therefrom to a point *c*, where it curves toward such edge, and then being reversed in 20 a wide curve crosses itself at *d* and then continues onward and toward the edge until it is lost in an ornamental line *e*, parallel with the outer edge of the dish. During its course the line *b* is interrupted by small dots, as *h h*, 25 and by two outline trefoils *f* and *g*, the axis of the middle leaf of which in each case co-

incides with the direction of the line *b*. Springing from the quatrefoil *a* to the left is a similar line *b'*, curved in precisely an opposite direction to the line *b* and ornamented at similar places by the outline trefoils *f'* and *g'* and the dots *h' h'*. Between each panel containing the design formed by the central quatrefoil *a* and the lines *b* and *b'* and their ornaments is placed a cusp-like figure *x*, springing from the edge of the plate and pointing toward the center, and between it and the center is placed a trefoil *y*, the axis of the middle leaf of which is a radial line of the dish. This figure is repeated around the dish 40 a number of times, as shown.

30 What I claim as new is—

35 The design for a dish substantially as shown and described.

Witness my hand this 26th day of August, 45 1898, in the presence of two subscribing witnesses.

WILLIAM H. GRINDLEY.
